UNITED STATES PATENT OFFICE.

ARTHUR W. McCURDY, OF MALAHAT, BRITISH COLUMBIA, CANADA.

MEANS FOR FACILITATING SHARPENING OF AUGERS OR BITS.

Continuation of application Serial No. 548,796, filed April 1, 1922. This application filed November 11, 1922. Serial No. 600,469.

To all whom it may concern:

Be it known that I, ARTHUR W. McCURDY, a subject of the King of Great Britain, residing at Malahat, British Columbia, Canada, have invented certain new and useful Improvements in Means for Facilitating Sharpening of Augers or Bits, of which the following is a specification.

This invention pertains to an improved means for facilitating the accurate sharpening of augers or bits.

The structure is such that it may be readily positioned on the bit and its gage and guiding surfaces for the sharpening tools quickly brought into proper juxtaposition with the cutting edges or elements of the bit which is to be sharpened.

Augers or bits to maintain them in proper working condition, require that the cutting elements thereof be sharpened more or less frequently, and the angle or pitch of the cutting elements when sharpened should, of course, bear a fixed relation to each other and to the axis of the bit. The present structure is designed to produce a combined holder for the bit and a guide for the sharpening tool or tools which facilitates positioning and clamping of the bit and ensures the cutting away or sharpening of the cutting elements of the bit to the necessary extent and to the proper angularity.

One form of the combined clamp and guide, adapted more especially for the sharpening of a bit or auger such as set forth and claimed in my co-pending application, Serial No. 248,747, having a floor lip cutter formed on one of the spirals thereof and a chisel cutter formed as the continuation of the other spiral, is illustrated in the annexed drawings, wherein;

Fig. 1 is a sectional elevation of the holder and bit;

Fig. 2 a like view as seen at right angles to Fig. 1;

Fig. 3 a top plan view, with the bit or auger in place;

Fig. 4 a horizontal section on the line IV-IV of Fig. 1;

Fig. 5 a perspective view of the two elements of the clamp shown as separated; and

Fig. 6 a perspective view of the cutting end of the bit for which the guiding surfaces on the clamp for the sharpening tools are devised or arranged.

It will, of course, be understood that such

surfaces; both as to form and angularity, will vary according to the form and contour of the particular bit which it is designed or desired to sharpen.

The main body of the combined clamp and tool guide may be said to comprise a body 1 having a jaw 2 formed integrally therewith, the outer face of the jaw being flattened as at 3, while the inner face 4 is curved, such curved face being formed as an extension of the cylindrical bore or opening 5 which extends upwardly through the body and a head or extension 6 formed on the body. The body opposite jaw 2 is formed with a depending lug 7 in which is provided an elongated horizontally disposed slot 8.

Lug 7 is adapted to enter a socket or recess 9 formed in a second semi-cylindrical jaw 10 having a flat face 11 formed exteriorly of the jaw. A hinge pin 12 secured in the jaw and passing through slot 8 connects said movable jaw to the body of the clamp, permitting the movable jaw to move inwardly parallel to the opposite jaw so that the bit body denoted by 13 may be lightly clamped by a slight pressure exerted by the operator's fingers. The parallel flat faces 3 and 11 enable the clamp to be securely held in a vise when the bit is brought to its final adjusted position in the combined clamp and tool guide.

With a bit having a single floor lip cutter, as 14, and a single lip or chisel cutter 15, see Fig. 6, the head 6 is provided with an inclined guiding or tool bearing face 16, said face extending about or around the outer end to an extent slightly less than half the diameter of the head. Its lower end terminates adjacent an upstanding wall 17, while the higher end terminates in line with the wall 18 forming part of a cross groove or depression 19 likewise formed in the outer end of the head. Said groove which is interrupted by the bore 5 lies to one side of the center of said bore, so that when the bit is positioned its center pin or point 20 stands just outside of the groove. The groove is made wider at one end than the other and the outer wall thereof is curved outwardly to a slight extent, so that the sharpening tool may bring the chisel cutter down to a fine cutting edge.

A cross mark 21, Fig. 5, is provided upon the inclined tool guiding face 16 in order that the cutting elements of the bit may be

readily and accurately positioned with reference to the tool guiding surfaces. The clamp will preferably be produced from steel which is case hardened so that the guiding surfaces for the sharpening tools will remain unaffected thereby.

When the bit is positioned and clamped in place, the operator has only to pass a file or other sharpening tool over the floor lip 10 cutter 14 until such time as the tool takes a firm and full bearing on the guide face 16, by which time the lip cutter will be provided with a new and sharp cutting edge. A suitably shaped file is then brought to 15 bear against the lip cutter 15 and it is reduced and sharpened until the lip and the floor of the twist on which the cutter is formed lie or stand in alinement with the walls of the groove at which time the abrasive action of the cutter is arrested thereby.

It will be noted that the depth of the groove is such that the body of the twist upon the edge or land of which the chisel cutter is formed will be cut away or removed so 25 that it lies in a plane in rear of the floor lip cutter 14, as will be seen upon reference to Figs. 2 and 6.

This application is a continuation of my application Serial No. 548,796, filed April 1, 30 1922, as a renewal of my application Serial No. 261,367, filed as of November 6, 1918.

What is claimed is:

1. In a sharpening tool guide for augers and bits, the combination of a body having 35 an opening therein for the reception of the bit body; and a plurality of combined tool guiding and gage surfaces formed on the outer end of the body, said surfaces being fashioned to conform to the contour and angularity of the cutting elements of the bit.

2. In a sharpening tool guide for augers and bits, the combination of a body having an opening therein for the reception of the bit body; a flat inclined surface formed on 45 the end of the body and adapted to serve as a guide for the tool which acts upon the floor lip cutter of the bit; and a groove also formed on the end of the body, said groove serving as a guide and gage for the sharpening tool which acts upon the chisel cutter.

3. In a sharpening tool guide for augers and bits, the combination of a body having an opening therethrough for the reception 50 of the bit body; a flat inclined surface formed on the outer end of the body and ex-

tending through a distance less than one half of the circumference of the opening aforesaid, said surface serving as a guide and gage for the sharpening tool employed upon the floor lip cutter; and a groove extending 60 across the body and opening therein, said groove being arranged to one side of the axis of the body and serving as a guide and gage for the tool employed to sharpen the chisel cutter of the bit.

4. In a combined clamp and sharpening tool guide for augers and bits, the combination of a body having an opening extending therethrough for the reception of the bit body; guiding and gage surfaces formed on 70 the outer end thereof for the sharpening tools; and a clamping jaw hinged to the body and adapted when moved inwardly to cooperate with the opposite body portion to clamp the bit body.

5. In a combined clamp and sharpening tool guide for augers and bits, the combination of a body having an opening extending therethrough for the reception of the bit body; guiding and gage surfaces formed on 80 the outer end thereof for the sharpening tools; and a clamping jaw having a sliding hinged connection to the body and adapted when moved inwardly to cooperate with the opposite body portion to clamp the bit 85 body.

6. In a combined clamp and sharpening tool guide for augers and bits, the combination of a body portion having an outwardly extending end or head with an opening extending therethrough for the reception of the bit body; an inclined flat bearing and gage surface formed upon the end of said outwardly extending end, said surface extending about the opening short of one half 90 of the circumference thereof; a tool guiding groove or channel extending across such outwardly extending end, to one side of the axis of the holder and opposite to that of the inclined surface; and a clamping jaw having 100 a sliding hinged connection with the body and adapted when moved inwardly to cooperate with the opposite body portion to clamp the bit body, the outer face of the jaw and the corresponding face of the body 105 being flattened.

In testimony whereof I have signed my name to this specification.

ARTHUR W. McCURDY.
